UNITED STATES PATENT OFFICE.

ALISON W. TAFT, OF WOODSTOCK, VERMONT.

DESIGN FOR A METALLIC RAILWAY-TIE.

SPECIFICATION forming part of Design No. 30,490, dated April 4, 1899.

Application filed February 20, 1899. Serial No. 706,262. Term of patent 3½ years.

To all whom it may concern:

Be it known that I, ALISON W. TAFT, of Woodstock, in the county of Windsor and State of Vermont, have invented and produced a new and original Design for a Metallic Railway-Tie, of which the following is a description.

Figure 1 is a perspective view of a railway-tie, showing my new design. Fig. 2 is a plan view of the same.

As shown in the drawings, the leading feature of my design consists of the vertical inner faces *a a* of the outer rail-base-holding lugs and the backward or outward slope or inclination of the ends of the tie from the tops *b b* of the said lugs and the inward curve *c* of the upper ends of the inner rail-base and block holding lugs *d*.

e designates the vertical sides of the body of the rail.

f designates rectangular chambers or recesses for the reception of the wooden or other blocks or chairs for the vertical support for the rails, and *g g* are vertical strengthening-ribs.

Having described my design, I declare that what I claim as new and as of my invention is—

The design for a metallic railway-tie as herein shown and described.

In testimony whereof I have signed my name to this specification, in the presence of two subscribing witnesses, this 1st day of February, A. D. 1899.

ALISON W. TAFT.

Witnesses:

WILLIAM BATCHELDER,
WILLIAM S. JOHNSON.
